BERT R. PARROTT, OF JACKSON, MICHIGAN, ASSIGNOR TO THE PARROTT HEATER COMPANY, OF JACKSON, MICHIGAN, A CORPORATION OF MICHIGAN.

GAS-BURNER.

1,135,047.

Specification of Letters Patent.

Patented Apr. 13, 1915.

Application filed October 4, 1912. Serial No. 723,987.

To all whom it may concern:

Be it known that I, BERT R. PARROTT, a citizen of the United States, residing at Jackson, in the county of Jackson and State of Michigan, have invented a certain new and useful Improvement in Gas-Burners, of which the following is a full, clear, and exact description, reference being had to the accompanying drawings.

10 This invention relates to gas burners for heating purposes, and the general object of the invention is to provide a very efficient burner of that type.

15 More particularly, one of the important objects is to provide a simple structure adapted to thoroughly mix gas and air and give a perfect combustion irrespective of the pressure or caloric efficiency of the gas.

20 Another object is to adapt the burner, by very simple changes, for natural gas, artificial gas or gasoline vapor.

25 Other objects are to so arrange the burner that the flame will be directed in a most efficient manner, concentrating the heat as desired; and to protect the burner from dirt, condensation and corrosion, thereby increasing its efficiency.

30 The simplicity of the construction, enabling cheap manufacture and easy installation, are also features of the burner shown and claimed herein.

35 The invention consists of the characteristics hereinafter more fully explained by which the above objects, or any of them, are attained.

40 In the drawing, Figure 1 is a side elevation of the burner, together with the shell and legs of a suitable stove or heater co-acting therewith; Fig. 2 is a face view of one of the burner sections, that is, looking radially from the axis of the annular burner; Fig. 3 is a vertical cross-section of the burner-section shown in Fig. 2; Fig. 4 is a bottom plan of such burner section with 45 the ends of the burner section head reversed with relation to Fig. 2; Fig. 5 is an enlarged view of a peculiar form of screen which is employed at the burning openings, the intermediate portion of this screen being 50 omitted in the drawings for simplicity.

55 Referring by numerals to the parts shown in the drawing, 10 represents a gas conduit which may be a hollow ring to which gas is supplied through a pipe 11. The ring is supported in any suitable manner. As indi-

cated by Fig. 1, it may be suspended below a heater casing 12 supported on legs 13. Extending from the ring at suitable intervals are nipples 15 which connect with the burner sections. These nipples are "spuds" or bushings screwed into bosses 16 on the upper surface of the ring, the bushing having a bore varying in cross section with the kind of gas it is intended to use.

The burner is made up of abutting segments which, together, have the form of a ring, each segment having a tubular leg connected with a corresponding nipple 15. The segments are designated 20 in the drawing. In the form shown, there are six of them, each extending for substantially 60°. Each segment 20 is a hollow device having a bottom 21, an outer arcual wall 22, a top composed of the inclined portion 23 and the inwardly overhanging horizontal portion 24 and ends 25 and 26. The bottom 21 of the segment has a centrally placed aperture, and surrounding this aperture, and leading downwardly and made integral with the segment, is the hollow leg 28. The intermediate portion of the leg is shown as round, connected by a flaring flattened port 27 with the head; near its lower end the leg has a round flaring portion, as indicated at 29, and extending crosswise of this lower flared portion is an integral cross bar 30, having a central opening 31. The burner section described is preferably a single casting.

When the burner sections are in place the upper ends of the nipples 15 occupy the openings 31. The nipple is shown in Fig. 3 as having its lower portion somewhat larger than the opening 31, whereby a shoulder is provided on which the cross bar 30 rests, whereby the section is supported, while leaving an unobstructed air space around the nipple. Below the cross bar 30 and within the leg 28 is a circular piece of screen cloth 34 held in place by a partially circular ring 35 which is sprung into an annular recess 36 on the inner face of a depending and outwardly beaded portion 36 of the leg.

When the sections are set on the nipples, the end walls of the adjacent sections abut. In this position, a tongue or dowel pin 40 on one end of the section occupies a corresponding recess 41 in the adjacent end of the next section, whereby the segments of the section are held in their annular positions. It is simply necessary to place such sections to-

gether, to give them the annular assembly shown in Fig. 1, and then the various legs are shoved downwardly onto the nipples, after which the structure retains its position 5 without other fastening.

The front of the segment casting (that is the concave vertical side) is open practically throughout the arcual length. Near the ends of this open space, however, are ears 10 43 (Fig. 3) projecting inwardly from the end walls, and these ears form points to which the burner facing may be secured. This facing consisting of a perforated screening strip 44, preferably of brass, having small holes 45, and outside of this, a 15 facing strip 46, preferably of iron and having much larger holes 47. Both strips are shown as secured to the segment or head by screws 48 which pass through the two strips 20 into the ears 43 referred to.

The screen 44 is formed in a peculiar manner, as shown in Fig. 5. That is to say, the perforating openings 45 are not round, but are elongated or rectangular, the operation 25 of which is to spread the flame horizontally, thus concentrating it in a horizontal sheet and giving a more effective heating than where it flares in a conical form from a round opening.

30 The spuds 15 furnish the means which make the burner adjustable for different kinds of gas. For artificial gas the bores through these spuds are made comparatively large; for natural gas comparatively small; 35 and for gasoline gas they have an intermediate size. These sizes are so chosen that the total area of the bores for burners for different gases is proportional to the heat units in the gas to be consumed. The actual size of 40 the openings 47 in the facing is determined with reference to the area of cross section of the bore of the mixing leg, to obtain the proper mixture. With the bore of the spuds chosen with reference to the kind of gas 45 used, the pressure of such gas is immaterial. If the gas pressure is high the gas velocity draws in with it a comparatively large amount of air through the screen 35. If, on the other hand, the gas pressure is low, the 50 slow velocity draws a correspondingly small amount of air. The proper mixture, therefore, is preserved in any case. By simply changing the nipples for different kinds of gas a much simpler structure and operation 55 is obtained than where mixing chambers of adjustable size are employed.

The inward overhang of the top walls 24 of the segments, above the burner facings, as shown particularly at 49 in Figs. 2, 3 and 4, 60 is of importance, as it protects the burner from dirt, condensation and corrosion. The segmental form of the burner and the locking by means of the dowel pins, holds the burner sections in place when installed, but 65 allows the easy removal of sections for clean-

ing or renewing the screens or facings or changing the face plate for one with different orifices for different kinds of gas.

The circular form of the burner concentrates the heat at the center portion of the 70 circle, and still allows a full supply of secondary air from directly below the flame. This is an important feature in efficient heating. In connection with this, the spreading of the flame by the longitudinally slotted 75 screen is valuable, the flame lying in a thin, flat layer and thus allowing a greater amount of secondary air.

This burner may be constructed extremely 80 cheaply. The segment with the hollow legs and the cross bars is preferably a single integral casting. The brass screen may be manufactured in strips, as well as the iron facing. The lower screen at the foot of the leg is easily installed and effectively held in 85 place, being clamped at the edge and lying against the under face of the cross bar 30 and coming between it and the shoulder of the supporting nipple.

Having thus described my invention, what 90 I claim is:

1. In a gas burner, the combination of a series of burner sections arranged annularly and each consisting of a hollow segmental head and a hollow leg extending therefrom, 95 a series of nipples for conveying gas to the lower portions of said legs, there being an air opening into the leg about the gas inlet, the inner face of the head having an opening, a screen arranged vertically on said 100 opening, a perforated facing strip, and means for securing the facing strip and screen together across the opening in the inner face of the head, the head having an overhanging top portion which extends inwardly beyond the screen and facing strip.

2. In a gas burner, the combination of a series of burner sections arranged annularly and each consisting of a hollow segmental head and a hollow leg extending therefrom, 110 and means for conveying gas to the lower portion of said leg, there being an air opening into the leg, the inner face of the head having an opening which is covered by a perforated facing having narrow horizontal 115 openings.

3. A burner section made of approximately T-shape consisting of a hollow segmental head and a hollow leg, the leg communicating with the head, the inner curved face of the head having an opening, a screen over 120 said opening having narrow horizontal perforations, and a burner facing extending over it and having larger openings, the screen and facing being secured to the inner 125 face of the head.

4. A gas burner section consisting of a hollow segmental head and a hollow leg extending therefrom and having gas and air openings at its lower end, the inner face of 130

the head having an opening, a screen strip across said opening having narrow horizontal perforations, a facing strip surmounting said screen and having larger openings than those of the screen, and an inwardly projecting flange carried by the head and overhanging the screen and facing strip.

5. A gas burner section of approximately T-shape, the head of which is segmental having an opening on its inner face, a flat screen strip having narrow horizontal burner openings and secured across said opening in the head, a surmounting strip having a series of larger openings, inwardly extending ears at each end of the burner openings, and screws extending through said ears.

6. The combination of a gas conveying

means, a series of sectional burner members, each section having a segmental head and a depending hollow leg, means on the conveying means for engaging the leg for carrying the sectional burner members and conveying gas thereto, the head of the sections abutting each other at their ends to form an annular core, said head having coöperating lugs and recesses for interlocking the adjoining ends with each other.

20 In testimony whereof, I hereunto affix my signature in the presence of two witnesses.

BERT R. PARROTT.
